CLAIM

The ornamental design for a medical charging cabinet, as shown and described.

DESCRIPTION

FIG. 1 is a front perspective view of a medical charging cabinet.

FIG. 2 is a back perspective view of the medical charging cabinet of FIG. 1.

FIG. 3 is a front view of the medical charging cabinet of FIG. 1.

FIG. 4 is a back view of the medical charging cabinet of FIG. 1.

FIG. 5 is a right side view of the medical charging cabinet of FIG. 1.

FIG. 6 is a left side view of the medical charging cabinet of FIG. 1.

FIG. 7 is a top view of the medical charging cabinet of FIG. 1; and,

FIG. 8 is a bottom view of the medical charging cabinet of FIG. 1.

1 Claim, 8 Drawing Sheets
